CARBURETOR

Filed Dec. 21, 1925

UNITED STATES PATENT OFFICE.

JOSEPH AUDINO, OF EAST BRADY, PENNSYLVANIA.

CARBURETOR.

Application filed December 21, 1925. Serial No. 76,789.

This invention relates to improvements in carburetors pertaining more particularly to a carburetor of the type having no float but feeding a direct flow of gasoline to the carburetor and controlling said flow by an automatic feed which in reality, takes the place of the float in the common and well known type of carburetor now on the market.

The primary object of the invention is the provision of means for feeding gasoline directly to the carburetor.

Another object of the invention is the provision of a carburetor in which gasoline is fed directly to the carburetor and the feed of said gasoline is controlled automatically through the medium of the engine speed.

Another object of the invention is the provision of a carburetor of the character described which will in operation, increase gasoline mileage and prevent engine knocking.

A still further object of the invention is the provision of a carburetor of the character described which is constructed in a manner to prevent fire in case the engine "backfires."

Another and further object of the invention is the provision of a carburetor of the character described which is cheap and simple of manufacture and readily adaptable as a replacement to the common form of carburetor usually found in use on hydrocarbon motors.

A still further object of the invention is the provision of a carburetor which is practically automatic in operation, thus avoiding the necessity of adjustment for use with different types of motors.

Other further objects and novel features of construction and improved results of the invention will appear in the following description and accompanying drawing:

In the drawing:

Figure 1 is a vertical sectional view of a carburetor made in accordance with this invention.

Figure 2 is an end view of the carburetor.

In describing the invention in detail, reference being had to the drawings in which like parts I have designated by similar reference numerals throughout the description, 5 represents the main body or casting of the carburetor which is provided at one end with a flange 6 having bolt openings 7 for fastening the carburetor in the usual manner to the intake manifold 8 of a hydrocarbon motor or the like. The casting or body portion of the carburetor is tapered slightly to-

ward its open end 9 so that this end of the body portion is slightly larger than the inner end. The open end 9 is closed by a door 10 which is preferably mounted on a hinge 11 and normally held in closed position by a suitable spring catch 12. The door is provided with an opening 13 to permit the passage of air into the carburetor and intake manifold.

The air control comprises a pivotally mounted shutter 14, the end 15 of which engages suitable depressions 16 in the face of the door so that the shutter will remain in any position set when operated by the handle 17.

It is readily apparent that by rotating the shutter 17, the size of the orifice can be varied at will.

Adjacent the inner end of the main carburetor housing or casting there is mounted a common form of butterfly throttle valve 18. The construction of this valve is conventional and comprises the valve 18 which is carried by a rotatably mounted shaft 19, the upper end of which extends through the carburetor casting and carries a bell crank 20, one end 21 of which is adapted to be connected with an operating member, which is usually lead for the sake of convenience to the dash board of the vehicle or to such other convenient position as to be readily operated at will. As is common in this construction, there is provided a stop 22 which is adapted to be engaged by the stop member 23 which forms a part of the bell crank.

Positioned within the carburetor, preferably at a point approximately intermediate its length, there is a regulator comprising a washer shaped member 24 and a flap valve 25. Due to the tapered walls of the casting 5, this member is held rigidly in place, although in the preferred form a set screw is provided which penetrates the outer wall of the carburetor and engages this member for further locking it in place. The flap valve 25 is pivotally mounted on the washer member as at 26 and closes the opening 27 in the washer. Rigidly attached to the valve so as to move therewith, there is an outwardly extending arm 28, this lever extending through the washer opening 27 to a point well in front of the washer.

Gasoline is fed to the carburetor by means of the supply pipe 29 which is in communication with a hollow casting 30 which is screw threadedly mounted in the plug 31,

which carries the needle valve 32. The plug 31 is a close fit in the opening 33 in the casting 5, being held in place by tension of the spring 34 which exerts an upward pressure 5 upon the L-shaped bracket 35 which bracket is in turn held in any desired position through the medium of the bolt 36 and nut 37 which form a part of the bracket 39 which is rigidly attached to the casting 5 as at 40.

10 The needle valve 32 operates on a tapered seat 41 and is provided with an extending portion or rod 42 which extends downwardly into the carburetor body at a point above the flap valve operating lever 28. The upward 15 movement of the needle valve is controlled by the adjusting screw 43 which extends downwardly through the chamber 30 whereby this extending end 44 is positioned at a point adjacent the upper face of the needle valve.

20 Suitably mounted on coil springs 45 positioned on the upper face of the control lever 28, there is a plate 46 which is normally in engagement with the lower end of the needle valve stem or pin 42.

25 A manual control for the flap valve 25 is provided in the form of a bell crank 47 which is adapted to operate the shaft 48 which in turn operates the forwardly extending lever 49 which is provided with a cup-shaped outer 30 end 50 which engages the rod 51. The rod 51 extends through the carburetor body 5 and upon the operation of the bell crank lever will engage the lever 28 so as to raise this lever and open the needle valve. The rod 35 51 is normally in the position shown in Figure 1 of the drawings, by reason of the coil spring 52.

Connection is led from the bell crank 47 to a point of convenience for operation, this 40 connection being made with the arm 53 of the bell crank.

Operation.

With the parts in the positions shown in 45 Figure 1, the gasoline feed to the carburetor is closed. To enable the starting of the motor, it is necessary to actuate the primer which comprises the operating arm 49, and rod 51, so as to raise the flap valve lever 28 which will cause the plate 46 to lift the needle valve and permit the passage of gasoline to the motor, it being understood when the arm 28 is elevated, the flap valve 25 is carried to an open position. In starting the 50 motor, the throttle control is always opened and for this reason the butterfly valve, which is actuated through the throttle control, will be in an open position and will permit the suction of gasoline into the intake manifold 55 of the engine.

After the engine is started, the operation 60 of the carburetor is automatic. As the butterfly valve is opened wider, a greater suction is created in the carburetor and this suction working on the flap valve 25 will pull

this valve further open and in so doing will elevate the outer end of the flap valve lever 28 which will in turn lift the needle valve to permit the passage of a greater amount of fuel.

The automatic operation of the carburetor can be controlled to a large degree by the position of the shutter 14 as the engine can suck a volume of air through the carburetor in amounts only in proportion to the size of 75 the orifice or opening 13.

The movement of the needle valve can be controlled by the regulating screw or stem 43.

From the foregoing it will be seen that I 80 have provided a carburetor for feeding fuel directly to the hydrocarbon carburetor and have eliminated the use of a float valve. Furthermore it will be seen that the operation 85 of the carburetor after the motor has once started, is automatic, and that fuel in proportion to the speed of the motor will be furnished for the reason that the speed of the motor controls the suction and velocity of the air through the carburetor housing or casting 5. As the motor speeds up, a greater amount of fuel is drawn into the intake manifold and likewise a diminishing amount of fuel is drawn in as the speed of the motor 90 decreases.

Furthermore, it will be seen that the construction of the carburetor is simple and that it can be readily substituted for carburetors now commonly in use and can be readily and easily attached to the intake manifold of hydrocarbon motors.

The function of the resiliently mounted plate is important, in that it permits the further opening of the flap valve after the needle valve has reached its limit of movement. Until the needle valve engages its stop 32 the springs below the plate 46 have not been compressed. If, after the needle valve has reached its stop and limit of movement, the throttle valve is opened wider, the 105 flap valve will be caused to open to a greater extent and this additional movement of the flap valve is accomplished through the compression of the plate springs 45. In other words, the limit of movement of the needle valve and flap valve is not the same nor is it reached at the same time. When the needle valve reaches its extreme open position enough gasoline can pass to the mixing chamber to supply the engine at any speed, provided sufficient air is supplied. The connection between the flap valve and needle valve is such as to permit a continued movement of the flap valve after the needle valve has reached its extreme limit of movement.

Having thus described my invention what I claim and desire to secure by Letters Patent is:

1. A carburetor comprising a mixing chamber having an air-intake and a fuel supply,

5 a needle valve in said fuel supply, said needle valve being normally closed and having an extending portion projecting into said mixing chamber, and an air-operated valve pivotally mounted in said mixing chamber and being provided with an extending member carrying a plate resiliently mounted thereabove and having engagement with the extending portion of the needle valve, whereby 10 10 said needle valve is opened and fuel is supplied in amounts in proportion to the volume of air admitted.

15 2. A carburetor comprising a mixing chamber having an air-intake and a fuel supply, a needle valve in said fuel supply, said needle valve being normally closed and having an extending portion projecting into said mixing chamber, an air operated valve pivotally mounted in said mixing chamber and being provided with an extending member carrying a plate resiliently mounted thereabove and having engagement with the extending portion of the needle valve, and adjustable 20 means to control the opening of the needle 25 valve, for the purpose described.

30 3. A carburetor comprising a housing forming a mixing chamber having an air-intake and a fuel supply, said fuel supply comprising a conduit extending into the mixing chamber and being adjustably mounted in respect thereto, a needle valve extending through said conduit having a portion projecting into the mixing chamber, and an air-operated valve pivotally mounted in the mixing chamber and being provided with an extending member carrying upon its top a resiliently mounted plate having engagement with the projecting portion of the needle valve, whereby 35 40 said needle valve is opened and fuel supplied in amounts in proportion to the volume of air admitted.

45 4. A carburetor comprising a mixing chamber having an air-intake and a fuel supply, a needle valve in said fuel supply, said needle valve being normally closed and having a projection into said chamber, an air-operated valve mounted in said chamber and positioned therein at a point intermediate the fuel supply inlet and outlet side of the chamber, and said air-operated valve being provided with an extending member carrying a resiliently mounted plate having engagement with the projecting portion of the needle valve for actuating the same.

55 5. A carburetor comprising a mixing chamber having an air-intake and a fuel supply, means at the inlet end of said chamber to control the inlet of air to the same, a needle valve in said fuel supply, said needle valve being normally closed and having a portion projecting into the mixing chamber, an air-operated valve pivotally mounted in the mixing chamber and positioned therein at a point intermediate the fuel supply inlet and outlet side of the chamber, said air-operated

valve being provided with an extending member carrying a resiliently mounted plate having engagement with the projecting portion of the needle valve for actuating the same, an adjustable stop for the needle valve 70 and said resiliently mounted plate acting as a resilient stop for the air-operated valve, for the purpose described.

6. A carburetor comprising a mixing chamber having an air intake and a fuel supply, 75 a needle valve in said fuel supply, said needle valve being normally closed and having a projection into said chamber, a washer mounted in said chamber and positioned therein at a point intermediate the fuel supply inlet and the outlet side of the chamber, an air operated valve pivotally mounted upon said washer and having an integral arm extending to a point beneath the needle valve and a plate resiliently mounted upon said arm and having engagement with the projecting portion of the needle valve for actuating the same.

7. A carburetor comprising a mixing chamber having an air intake and a fuel supply, 90 a needle valve in said fuel supply, said needle valve being normally closed and having its lower end projecting into said mixing chamber, an air operated valve pivotally mounted in said mixing chamber and positioned therein at a point intermediate the fuel supply inlet and the outlet side of the chamber, said air operated valve having an integral arm extending to a position beneath the projecting end of the needle valve, 95 and a plate resiliently supported upon said arm and having engagement with the extending end of the needle valve, whereby said needle valve is opened and fuel is supplied in amounts in proportion to the volume of 100 air admitted.

8. A carburetor comprising a tubular mixing chamber having an air intake and fuel supply, a needle valve controlling said fuel supply, said needle valve being normally closed and having an end projecting into said mixing chamber, an air operated valve pivotally mounted in said mixing chamber and positioned therein at a point intermediate the fuel supply inlet and the outlet side of the chamber, said air-operated valve normally closing said tubular chamber against the passage of air or fuel therethrough and provided with an arm extending lengthwise the said chamber to a position beneath the projecting end of the needle valve, and said arm having operative engagement with the extending end of the needle valve, whereby said needle valve is opened and fuel is supplied in amounts in proportion to the volume 115 120 125 of air admitted.

In testimony whereof I hereunto affix my signature.

JOSEPH AUDINO.
